UNITED STATES PATENT OFFICE.

EDWARD R. LUECK, JR., OF HOWE, NORTH DAKOTA.

ENVELOP.

1,198,362.

Specification of Letters Patent. Patented Sept. 12, 1916.

Application filed June 23, 1915. Serial No. 35,850.

To all whom it may concern:

Be it known that I, EDWARD R. LUECK, Jr., a citizen of the United States, residing at Howe, in the county of Morton and State 5 of North Dakota, have invented new and useful Improvements in Envelops, of which the following is a specification.

This invention relates to a method for making envelopes, and more particularly to 10 a method for applying a thread thereto adapted to be used for easily and readily opening the envelop, and the method consists in the novel steps hereinafter described and claimed.

15 In the accompanying drawing: Figure 1 is a plan view of a section of the paper from which the envelop blanks are cut, the said figure having the outline of the blanks indicated thereon and the threads positioned 20 upon the paper and the blanks. The other figures are detail views of the features of the invention.

In the manufacture of the envelop a large sheet or strip of paper 1 is used and the dies 25 for cutting the envelop blanks (not shown) are so arranged that when the paper 1 is passed under or between them, the blanks 2 indicated in Fig. 1 are cut from the strip. It will be observed that the end portions of 30 the blanks in adjacent rows overlap each other and the adjacent ends of the front sides of the envelop blanks in the adjacent rows are in alinement with each other longitudinally of the paper 1. At the time that 35 the paper is manufactured, or when it is in a soft condition, that is to say, after the pulp has been passed through the rollers, but before the same is permitted to dry, threads 3 are laid along the lines of the adjacent ends of the fronts of the envelop 40 blanks in adjacent rows. When the blanks 2 are cut from the paper 1 the threads are also severed and consequently each blank 2 is provided at the opposite ends of its front 45 side with sections of the thread 3. After applying the thread 3 it is pressed into the material constituting the paper or sheet 1, and thus the threads are embedded at one side of the sheet but the pressure of embed-

ding the threads is not sufficient to push 50 them entirely through the paper.

After the blanks 2 are cut as hereinbefore described they are folded up in any usual manner whereby the threads 3 are at the inner side of the envelop and extend from 55 corner to corner across the ends thereof. After the envelop has been closed and sealed in the usual manner, it may be opened by grasping one corner portion between the thumb and fore finger and tearing a part of 60 the corner away from the envelop and thus an end portion of one of the threads 3 is pulled out of the end of the envelop and the same is opened. By this arrangement it will be observed that a person who receives 65 the envelop, may at the time that he is observing the address, open the same and during the operation of opening the envelop there is no possibility of the contents of the envelop being torn or mutilated. Inasmuch 70 as the threads are at the inner side of the envelop and do not project beyond the edges thereof, there is no possibility for the same tearing out while the envelop is in transit.

From the above description taken in conjunction with the accompanying drawing, it will be seen that a simple and cheap envelop is provided and that the tearing thread may be easily and quickly manipulated for the purpose of opening the envelop. 80

Having described the invention what is claimed is:—

The method of making envelopes consisting in applying threads to paper in parallel rows while the paper is in soft or plastic condition, then pressing the threads into one side of the body of the material of which the paper is composed and in the absence of an adhesive, whereby the threads are left exposed at one side of the paper, and finally 90 cutting blanks from the paper which blanks also include sections of the threads.

In testimony whereof I affix my signature in presence of two witnesses.

EDWARD R. LUECK, JR.
